UNITED STATES PATENT OFFICE

149,556

DESIGN FOR A BICYCLE

Frank Charles Jaye, Cleveland Heights, Ohio, assignor to The Co-Operative Bicycle Manufacturing Company, Cleveland, Ohio

Application December 20, 1946, Serial No. 135,631

Term of patent 3½ years

(Cl. D90—8)

To all whom it may concern:

Be it known that I, Frank Charles Jaye, a citizen of the United States, residing in the city of Cleveland Heights, county of Cuyahoga, and State of Ohio, have invented a new, original, and ornamental Design for a Bicycle, of which the following is a specification, reference being had to the accompanying drawing, forming a part thereof.

Figure 1 is a side elevation of the bicycle showing my new design.

Figure 2 is a top view thereof.

Figure 3 is a front view.

Figure 4 is a rear view.

I claim:

The ornamental design for a bicycle, substantially as shown.

FRANK CHARLES JAYE.
